UNITED STATES PATENT OFFICE.

LÉON DELPEUCH, OF NEUILLY-SUR-SEINE, FRANCE.

COMPRESSED-AIR SUSPENSION FOR VEHICLES.

1,009,287.

Specification of Letters Patent. Patented Nov. 21, 1911.

Application filed December 17, 1908. Serial No. 468,039.

To all whom it may concern:

Be it known that I, LÉON DELPEUCH, a citizen of the Republic of France, residing in Neuilly-sur-Seine, Department of the Seine, France, have invented certain new and useful Improvements in Compressed-Air Suspensions for Vehicles, of which the following is a specification.

This invention relates to an improved compressed air suspension applicable to vehicles of all kinds, including aeroplanes. The said suspension is intended to replace the springs usually employed.

It comprises compressed air cushioning devices equal in number to the wheels, a cushioning device being interposed, similarly to a spring, between an end of the axle and the frame of the vehicle.

In the systems of compressed air suspension which have previously been employed, the compressed air serves in reality only to cushion sudden shocks or vibrations; but the expansion of the mass of air thus subjected to a shock takes place as rapidly as the shock itself, so that counter shocks are produced which interfere with the comfort of the passengers and strain the motor or other parts of the vehicle just as much as direct shocks.

The improved apparatus comprises the arrangement below the piston of each cushioning device, of a spring which is compressed and offers a resistance or back pressure when its cylinder rises as the result of excess load or stress at the other side of the vehicle, that is to say at the opposite end of the axle; consequently this spring assists in righting the vehicle and restoring equilibrium.

The improved compressed air suspension will be understood from the following description with reference to the annexed drawings in which:

Figure 1 is a diagrammatic plan of the system. Fig. 2 is a vertical section of one of the cushioning devices. Figs. 3 and 4 are diagrams illustrating the action of the apparatus.

For each wheel, that is to say at each end of the axles is provided a cushioning device comprising a cylinder A fixed vertically to the side of the frame B. In this cylinder works a piston C guided by a rod a the lower end of which is supported on the axle in any suitable way. The cylinder A is open at bottom and closed at top. Under the piston

and between same and a cross piece b fitted across the open end of the cylinder A is mounted a coiled spring R. The upper part of the cylinder A above the piston C communicates by a pipe c with a compressed air receiver Z common to the two cushioning cylinders of one axle.

d is a valve fitted in the pipe c and kept against its seat by a spring e. This valve is adapted to uncover the openings f when the space between the piston C and the end of the cylinder is reduced, so that the air driven back by this reduction of volume can pass through the openings f into the pipe c and receiver Z. The valve d is formed with a passage g of reduced section adapted to allow of the return of the expelled air under the conditions hereinafter explained.

If desired all four cushioning cylinders of the vehicle may be connected to one compressed air receiver by their pipes c, but it is preferable to couple them in pairs to one cylinder for each axle as described, especially in cases where the weight of the vehicle cannot be uniformly distributed. The action is moreover the same whatever may be the number of the receivers Z.

When a wheel is subjected to a shock owing to an obstruction or an inequality in the road, so that the piston C rises in the cylinder, the valve d opens and the air in the cylinder above the piston is thus at once put into communication with the receiver Z. The total volume of air which is thus subjected to the shock being much greater than that contained in the suspension proper, that is to say in the cylinders A, the system as a whole is very responsive and supple as regards its cushioning action. The consequence is that the pressure in the cylinder in operation at a given moment does not rise suddenly, as would be the case if the different cushioning devices were independent of each other, and were not connected to one or more receivers Z of relatively large volume as compared with that of the cylinder A.

When the obstacle is cleared, the piston C would tend to return to its original position by reason of the air pressure exerted above it, and it might return very rapidly to this position of equilibrium as is the case with the springs at present employed, thus causing a counter shock and vibrations as detrimental as a direct shock to the mechanism and the comfort of the passengers. But the

valve d has now come upon its seat, so that the air can only return slowly and gradually into the cylinder from the receiver Z through the small passage g in the valve. This passage 5 may be formed in the wall of the cylinder itself instead of in the valve.

A system comprising a number of cushioning cylinders, as above described can support different loads. When the load on the 10 vehicle is increased it is only necessary to increase the pressure in the receiver or receivers Z by means of any suitable pump.

In order to make good any loss of air which might occur an air pump or pumps 15 may be disposed between the frame and one or more of the axles, so that whenever a jolt occurs air is forced into the receiver or receivers Z . Further a valve may be provided within reach of the driver to enable 20 him to reduce the pressure in the receiver or receivers Z without dismounting from the vehicle, and a pressure gage can be provided in connection with the receiver or receivers to indicate the pressure therein.

25 The coiled spring R fitted in each cushioning device between the piston and the cross piece b in which the piston rod is guided, is not normally in action; the top coil of this spring hardly touches the bottom 30 of the piston C . In order properly to understand the part played by this spring in each of the cylinders connected to a given receiver Z , suppose each of these springs to have a resistance of 100 lbs. and suppose 35 that the line M . N (Fig. 4) represents the normal level of the frame of the vehicle and that the frame has tilted into the position M' . N' . The two pistons C . C' of the cylinders of one axle will have remained in their 40 previous position, *i. e.* in one horizontal plane. But cylinder A has moved down and cylinder A' has risen. The bottom of piston C in cylinder A is therefore away from the spring, which has moved down 45 with the cylinder A . Air above the piston C has been compressed and forced out of the

cylinder toward the receiver Z , it will return slowly into the cylinder through the passage g of valve d as before explained and the frame will reassume its normal level. 50 At the same time the other cylinder A' has risen, the result of which is to introduce the 100 lbs. resistance of the spring R' , and the action of this spring is therefore exerted between the piston C' and the cross piece b' of 55 cylinder A' . The spring R' therefore acts as a back pressure or resistance and tends to right the vehicle which has tilted under the effect of a momentary excess load at the opposite side of the vehicle viz. that at which 60 the cylinder C is mounted.

In the foregoing description the cylinders are assumed as fixed to the frame and the piston rods as connected to the axles. It will be understood that with the same 65 method the cylinders could be supported on the axles and the pistons be connected to the frame.

What I claim and desire to secure by Letters Patent is:

A compressed air suspension for vehicles comprising cushioning devices equal in number to the wheels of the vehicle, and comprising pistons and cylinders connected one to the frame and the other to the axle, 75 a spring in each cushioning device applied to the under side of the piston and to the bottom of the cylinder and opposing the expansion of the air and reacting so as to increase the pressure in the reservoir and to 80 transmit this pressure to the opposed cushioning device, whereby to reestablish equilibrium where the vehicle is inclined under an excessive load.

In witness whereof, I have hereunto signed my name in the presence of two subscribing witnesses.

LÉON DELPEUCH.
